Patented Aug. 29, 1922.

UNITED STATES PATENT OFFICE.

ANSEL C. HULBERT, OF SAN FRANCISCO, CALIFORNIA.

ELECTRIC WATER HEATER.

1,427,596.

Specification of Letters Patent. Patented Aug. 29, 1922.

Application filed June 11, 1921. Serial No. 476,783.

To all whom it may concern:

Be it known that I, ANSEL C. HULBERT, a citizen of the United States, residing at San Francisco, in the county of San Francisco and State of California, have invented certain new and useful Improvements in Electric Water Heaters, of which the following is a specification.

This invention relates to electric heating devices, and is especially designed for use in heating water.

One of the objects of my invention is, to obtain a greater heating surface than has been attained in prior devices, without materially increasing the space occupied by the heater.

A further purpose of this invention is, to encase the heating element in a continuous metal tube which is returned upon itself, so that the ends may be sealed into a single plug.

In the following description, I shall refer to the illustrations in the accompanying drawing, in which:—

25 Figure 1 is a perspective view of the complete heater showing the device in position in a reservoir connected to a water pipe.

Figure 2 is a perspective view, partly broken away, of the upper part of the heating element and its enclosing tube.

30 Figure 3 is a perspective view of the heating element with its cover or tube partly torn off, and certain insulating elements bent away from the core.

35 Figure 4 is an enlarged detail longitudinal section through the central part of the heating element and its cover or tube.

Figure 5 is a section on the line 5—5 of Figure 4.

40 Fig. 6 is a vertical sectional view of the upper portion of the heater.

In the embodiment of the invention shown in the accompanying drawings, there is provided, a heating element having a core 10 which consists of a flat strip of asbestos or other like insulating material which may or may not have its edges notched, or serrated to receive the wire. Around each end of this strip is wound resistance wire 11, the wire on the end being wound in one direction, as right handed, while the wire on the other end is wound in the opposite direction or left handed. In order to accomplish this winding and at the same time hold the central portion of the winding tightly in place, without bringing too great

strain thereon, when the heating element is bent to complete the heater, the center of the core 10 is notched as at 12 on the side which eventually forms the inside of the 60 bend. Spaced at each side of this notch, is an opening 13, and the ends of the wire are run through respective openings, so as to leave a central portion 14 connecting the coils. At each end of the core, there is also 65 provided an opening 15 through which the respective wire end is threaded. In order to hold the convolutions of the coils apart, an insulating strand 18 is wound around the core between said convolutions.

70 Extending longitudinally of the core and covering the resistance wire and insulating strand, is a pair of channel shaped insulating strips 17 preferably formed of mica or other like heat resisting insulating material. The respective wire ends are soldered, or otherwise permanently secured to terminals 18 and the entire element, with the exception of these terminals is covered by a metallic 75 protecting tube or cover 19 fitting closely over the channel shaped strips.

75 After the heating element is assembled in this manner, the tube and contained element are doubled at the center with the notch 12 inward, so as to form a narrow U-shaped structure, and the ends are then firmly soldered or brazed to a hollow plug 20 with the terminals 18 projecting up therethrough. These terminals run through an insulating plate 21 and have the lower 80 ends of binding posts 22 connected thereto. A second insulating plate 23 is fitted on the plate 21 and held to the plug by screws 24. The binding posts project through this plate 23 and carry the usual knurled nuts 25.

85 It is obvious that various changes may be made in the form and construction of the apparatus, without departing from the material principles of the invention.

90 Having thus described the invention, what is claimed as new, is:—

95 1. An electrical heating element comprising a connecting supporting plug, having terminal connectors, a U-shaped metal tube having its ends soldered or brazed to said plug, and a helically coiled resistance wire extending through said tube, and having its ends joined to said terminal connectors.

100 2. An electrical heating element including a core of heat resisting insulating material, a resistance wire wound on said core in spaced convolutions, a plurality of trough

shaped insulating strips extending longitudinally of the core and fitting closely on the wire windings, and a tube fitting closely on the strips, and extending from end to end thereof to hold said strips in position and protect the insulation, the windings and the core.

3. An electrical heating element including a core of heat resisting insulating material, a resistance wire wound on said core in spaced convolutions, insulating strips covering said wire windings, and a protective tube fitting over said insulating strips and completely covering the same, said tube and the parts therein being medially bent to produce a U-shaped structure having closely arranged legs.

4. An electrical heating element including a core of heat resisting insulating material, a resistance wire wound on said core in spaced convolutions, a plurality of trough shaped insulating strips extending longitudinally of the core and fitting closely on the wire windings, and a tube fitting closely on the strips, and extending from end to end thereof to hold said strips in position and protect the insulation, the windings and the core, said tube and the parts therein being medially bent to provide a U-shaped structure having closely arranged legs.

5. An electrical heating element including a core of heat resisting insulating material, a resistance wire wound on said core in spaced convolutions, insulating strips covering said wire windings, a protective tube fitting over said insulating strips and completely covering the same, said tube and the parts therein being medially bent to provide a U-shaped structure having closely arranged legs, a plug having said legs fixed thereto, and wire connection devices carried by and insulated from the plug, one of said devices being connected electrically to one

of the ends of the resistance wire and the other of said devices being connected to the other end of said resistance wire.

6. An electrical heating element including a core of heat resisting insulating material, a resistance wire wound on said core in spaced convolutions, a plurality of trough shaped insulating strips extending longitudinally of the core and fitting closely on the wire windings, a tube fitting closely on the strips and extending from end to end thereof to hold said strips in position and protect the insulation, the windings and the core, said tube and the parts therein being medially bent to provide a U-shaped structure having closely arranged legs, a plug having said legs fixed thereto, and wire connection devices carried by and insulated from the plug, one of said devices being connected electrically to one of the ends of the resistance wire and the other of said devices being connected to the other end of said resistance wire.

7. That method of forming an electrical heater which consists in winding a resistance wire on a flexible insulating core, covering the core and wire with insulating strips, inserting the covered core and wire in a closely fitting tube, and bending the assembled article at its middle to form a U-shaped structure.

8. That method of forming an electrical heater which consists in winding a resistance wire on an insulating core, covering the core and wire with insulating strips, inserting the covered core and wire in a closely fitting tube, bending the assembled article at its middle to form a U-shaped structure, and connecting the extremities of said tube fixedly to a plug.

In testimony whereof I affix my signature.

ANSEL C. HULBERT.
